UNITED STATES PATENT OFFICE

WILLIAM J. A. LONDON, OF HARTFORD, CONNECTICUT, ASSIGNOR TO PEABODY ENGINEERING CORPORATION, OF NEW YORK, N. Y., A CORPORATION OF NEW YORK

APPARATUS FOR PULVERIZING MATERIALS

Application filed February 12, 1929. Serial No. 339,333.

My invention relates to apparatus for reducing materials to a powdered condition and more particularly for producing powdered coal for power plants. The invention will be understood from the following description taken in connection with the accompanying drawings in which Fig. 1 is a view in elevation, with certain parts in section, and Figs. 2 and 3 transverse sections on the planes of the lines 2—2 and 3—3, respectively, of Fig. 1.

Referring to the drawings, the apparatus illustrated is enclosed within a suitable housing which, for convenience of description, may be considered as divided into three sections forming chambers designated generally by the letters A, B, and C. The mill, of whatever type, for effecting the pulverization of the material is housed within the chamber A. From said chamber the material is caused to flow through the chambers B and C in a current of air induced by a fan connected to the outlet of chamber C. In these chambers a separation is effected between the fines and unground material in the manner hereinafter described. Any suitable design of housing may be employed to accommodate and support the several parts of the pulverizer.

The mill shown, designated by the numeral 1, is that of the impact type, that is, one by which the reducing action is effected by the impact of rotating hammers. This mill is supported upon a base 2 which includes bearings 3 and a shaft 4. The latter extends into the upper part of the housing as indicated in Fig. 1. It is driven through a suitable connection with a motor 5.

Located within the chamber A and secured to the shaft 4 is a disc 6 having secured thereto a plurality of hammers 7. The material to be pulverized is delivered from a hopper 8 to a feeder 9 and thence through a chute 10 to the mill.

Above the mill is the chamber B, the inner wall 11 of which is a frustum of a cone with its smaller open end directly over and in communication with the outlet 12 of the mill. Above the chamber B is the chamber C, the wall 13 of which is also a frustum of a cone,

the base of which coincides with the larger end of chamber B. To the outlet end of chamber C is secured a pipe 14 connected to an exhaust fan 15 by which a current of air is induced to flow through the pulverizer, the air entering through a valved pipe 1 connected to chamber A below disc 6.

The chamber B may be defined as a classification chamber and C as a continuation thereof, into which the usable fines are drawn after their separation from the coarser or unground particles. I prefer that chamber B shall be located directly above the mill and in direct communication therewith so as to provide a free and unobstructed inlet into said chamber.

The principle of operation of the pulverizer as above described is as follows:

Assuming that coal is the material to be treated and that it is to be reduced to a fineness of 200 mesh I start with it in the condition in which it is delivered from the mine, that is, with its moisture content and without previous drying, although this is not essential. The coal is fed to the mill in a practically continuous stream and will be subjected to the action of the mill as soon as a given mass is brought into contact with the rotating hammers 7. The reduction will not be uniform but will vary by way of example from 50 to 200 mesh. The suspended material in the mill will be set in rapid motion by the hammers and will be swept through outlet 12 by the current of air induced by fan 15 into chamber B. By reason of the expanding form of chamber B there will be a reduction in velocity of the moving mass which will permit all particles which are of a size below the ultimate mesh to fall back into the mill to be further subjected to the action of the hammers.

The suction effect of fan 12 will be so adjusted and the height and cross-sectional areas of chambers B and C so proportioned that only the lighter particles, that is, those of the ultimate fineness will reach the upper part of chamber C and will be carried away by the fan. The heavier particles, or those which have not been reduced to ultimate fineness, will fall by gravity from the flowing stream according to

their size, that is, the heavier particles, say those of 50 to 100 mesh, will be returned to the mill after a comparatively short travel in chamber B. The finer particles will be lifted 5 further until there remains in the upper part of chamber C only those particles of the desired or ultimate fineness.

While I have shown an impact mill this does not exclude the possibility of some of the 10 material being reduced by attrition, this being due to the condition existing in the mill itself and of the action of the particles upon one another as they are swept around the mill by the rotating hammers.

15 The above being the general mode of operation contemplated by me, the efficiency of the pulverizer may be increased by the employment of some or all of the following devices illustrated in the drawings.

20 In Fig. 1 I have shown a plate 16 attached to shaft 4 near the upper end thereof and in approximately the plane of the outlet of chamber B. As the stream of pulverized material flows upward the plate 16 offers an obstruction which will, to a more or less extent, retard the stream and tend to throw the heavier particles against the conical wall 11 and thus assist in the classification of the particles.

To reduce unnecessary windage in the 30 pulverizer and to insure better circulation, I may introduce an annular plate 17 secured by suitable means to the wall of chamber A so as to afford a passage between the plate and the upper wall of the chamber. As indicated by the 35 arrows, the material being treated will be thrown outward by the hammers 7 toward the outer wall of chamber A and will flow in a substantially even and uniform stream through the passage above the plate 17. Some of the heavier particles will drop back 40 into the path of the hammers while the other and lighter particles will be carried by the air current through outlet 12 into the classification chamber B where a separation of the fines from the heavier or coarser particles will 45 be effected in the manner before described.

Between the plate 17 and the upper wall of the mill chamber A I may introduce vanes 18 for the purpose of lengthening or shortening 50 the path of the stream, according to the position of the vanes, from the hammers to the outlet 12. These directing vanes may be placed as desired and as indicated by the full and broken lines in Fig. 3.

55 To further facilitate the clearing of the mill I may provide it with one or more elevating planes 19. These tend to lift the material more readily from the hammers to the outlet 12. The inclination of these planes as shown 60 in Fig. 1 is about 45°. This inclination may be varied according to the material being treated.

The plates 16 and 17, the vanes 18 and the elevating planes 19 I have introduced into the 65 pulverizer to increase its efficiency and to fa-

cilitate the carrying out of the main purpose of the invention which is to effect the separation of the fines in the classification chamber B somewhat in the manner indicated by the arrows 20 in said chamber, immediately after the impact and attrition forces in the mill have acted upon the material being treated, and the return of the coarser particles to the mill for further treatment.

The velocity of the induced air current 75 which carries the material from the mill will be so controlled as to create a condition in the classification chamber as will permit the desired separation between the fines and the coarser particles to be substantially completed 80 before or immediately after the material enters the outlet chamber C. This, of course, is not absolute but the purpose is that the material entering chamber C will be reduced to the desired or ultimate mesh fineness so that a 85 substantially uniform product, particularly if powdered coal, may be delivered to the burners direct through the pipe connection 21.

What I claim is:

1. A pulverizer comprising a casing having 90 an outlet in the upper part thereof, hammers supported within the casing, means for rotating said hammers, means for delivering the material to be pulverized into the casing, and deflecting blades between the outer ends of 95 the hammers and the wall of the casing and inclined from the bottom of the casing toward the outlet for directing the material away from said hammers, to the outlet.

2. A pulverizer comprising a stationary 100 casing having an outlet in the upper part thereof, hammers supported within the casing, means for rotating said hammers, means for delivering the material to be pulverized into the casing, deflecting blades fixed within 105 the casing on a circle of greater diameter than the path of the rotating hammers, and means for causing a current of air to flow through said casing.

3. A pulverizer comprising a casing, a 110 plate near the upper wall of the casing for separating the chamber within the casing into upper and lower portions, a wheel carrying hammers supported in said lower portion, deflecting blades between the hammers 115 and the wall of the casing for directing the material away from said hammers into the space between said plate and the casing, said casing having an outlet in the upper wall thereof, and means for withdrawing the pulverized material through said outlet.

4. A pulverizer comprising a casing having an outlet in the upper part thereof, an annular plate supported within the casing and spaced from the upper wall thereof, a 125 wheel supported in the lower part of the casing and having hammers thereon, means for rotating said wheel, and deflecting blades between the hammers and the wall of the casing and inclined upwardly and outwardly from 130

- points adjacent the outer ends of the hammers for directing the material away from said hammers into the space between said plate and upper wall of the casing.
5. A pulverizer comprising a casing having an outlet in the upper part thereof, a wheel supported in proximity to the lower ride of the casing, hammers on said wheel terminating in spaced relation to the side of 10 the casing means for rotating said wheel, means for introducing the material to be pulverized into the casing in the path of the hammers, deflecting blades between the outer ends of the hammers and side of the casing for 15 directing the pulverized material from the hammers to the curved side of the casing, and means for withdrawing the pulverized material through said outlet.
6. A pulverizer comprising a casing having an outlet in the upper part thereof, a 20 wheel carrying hammers supported in proximity to the lower side of the casing, means for rotating said wheel, an annular plate supported within the casing above said hammers 25 and spaced from the upper wall of the casing to provide a passage around the side and top of the casing for the pulverized material, vanes in said passage, and means for causing a current of air to flow through said casing 30 and passage for conveying away the ground material, to the outlet.
7. A pulverizer comprising a casing having an opening in its top, a separating chamber extending above the casing communicating with the opening and provided with an 35 outlet, a shaft mounted through said casing and extending into the separating chamber, hammers supported on said shaft in the lower portion of the casing, means for rotating said 40 shaft and hammers, means for delivering materials to be ground into the casing in the path of the hammers, the wall of the casing beyond the hammers being curved, and deflector blades in the casing between the hammers 45 and the curved wall and inclined to direct the materials from the hammers toward the separating chamber.
8. The structure of claim 7 wherein the separating chamber has a conical wall 50 leading to the outlet and a baffle is mounted on the shaft between the outlet and the opening in the casing.

Signed at New York, in the county of New York and State of New York, this 16th day 55 of January A. D. 1929.

WILLIAM J. A. LONDON.
